(57) **CLAIM**

The ornamental design for a magnetic pen container, as shown and described.

DESCRIPTION

FIG. 1 is a front, right and top perspective view of a magnetic pen container, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of a second embodiment of a magnetic pen container showing my design.

FIG. 10 is a rear, left and bottom perspective view of the second embodiment of the magnetic pen container of FIG. 9.

FIG. 11 is a front elevation view of the second embodiment of the magnetic pen container of FIG. 9.

FIG. 12 is a rear elevation view of the second embodiment of the magnetic pen container of FIG. 9.

FIG. 13 is a left side elevation view of the second embodiment of the magnetic pen container of FIG. 9.

FIG. 14 is a right side elevation view of the second embodiment of the magnetic pen container of FIG. 9.

FIG. 15 is a top plan elevation view of the second embodiment of the magnetic pen container of FIG. 9; and,

FIG. 16 is a bottom plan elevation view of the second embodiment of the magnetic pen container of FIG. 9.
